DESIGN FOR A BOTTLE

Elsa Schiaparelli, Paris, France, assignor to Societe Anonyme Schiaparelli, Paris, France, a corporation of France

Application September 17, 1936, Serial No. 64,894

Term of patent 14 years

To all whom it may concern:

Be it known that I, Elsa Schiaparelli, a citizen of the Republic of France, residing in the city of Paris and Republic of France, have invented a new, original, and ornamental Design for a Bottle, of which the following is a specification, reference being had to the accompanying drawing forming a part thereof.

In the drawing:

Fig. 1 is a top plan view of a bottle showing my design.

Fig. 2 is a front view.

Fig. 3 is a side view.

Fig. 4 is a bottom view.

I claim:

The ornamental design for a bottle as shown.

ELSA SCHIAPARELLI.
